UNITED STATES PATENT OFFICE.

JOHN HICKMAN ENGLEMAN, OF EMORY, TEXAS.

CRANK FOR DRILLING-MACHINES.

No. 838,700.

Specification of Letters Patent.

Patented Dec. 18, 1906.

Application filed March 31, 1905. Serial No. 253,131.

To all whom it may concern:

Be it known that I, JOHN HICKMAN ENGLEMAN, a citizen of the United States, residing at Emory, in the county of Rains and State of Texas, have invented a new and useful Crank for Drilling-Machines, of which the following is a specification.

This invention relates to cranks for drilling-machines.

10 The object of the invention is to provide novel means whereby the drill may impart full free force of its blow, the lifting of the drill may be effected in a rapid manner and with the least possible wear upon the drilling-rope, and the stroke of the drill may be varied whenever found necessary or desirable.

With the above and other objects in view the invention consists of certain novel features of construction and combinations of 20 parts, which will be hereinafter more fully described, and pointed out in the claims.

In the accompanying drawings is shown the preferred form of the invention.

In the drawings, Figure 1 is a view of a 25 portion of a drilling-machine, showing my improved crank used in connection therewith; and Fig. 2 is a detail sectional view of the crank on an enlarged scale.

Referring to the figures by characters of 30 reference, A is a well-drilling machine of any preferred form and embodying in its construction shaft-sections 17, disposed in alignment and spaced apart at their inner ends. Arranged upon these shaft-sections is a 35 crank 18, comprising a pair of sleeves 19, which are suitably secured to the shaft-sections. Each sleeve is provided with a longitudinally-channelled arm 20, which extends at right angles therefrom and is provided

with a longitudinal slot 21. Disposed within 40 the channels of the arms are the members 22 of a yoke, the bend or crest 23 of which carries a grooved sheave 24. The members 22 of the yoke carry bolts 26, which project through the slots 21 and carry nuts 27 on 45 their outer ends, by which they may be clamped at any desired adjustment. It will therefore be seen that by loosening the nuts 27 the yoke members 22 may be moved to and from the shaft portions, and thus 50 lengthen or shorten the throw of the crank, as may be desired. By providing a crank of this character the drill-rope of a drilling-machine may be placed upon the sheave and the stroke of the drill will be regulated according 55 to the length to which the crank is adjusted.

I claim—

1. A crank for drilling-machines comprising a pair of longitudinally-channelled arms, sleeves carried by said arms, a two-part shaft 60 secured in the sleeves, and a yoke adjustably mounted in the channels of the arms.

2. A crank for drilling-machines comprising a two-part shaft, oppositely-disposed alining sleeves mounted on the adjoining 65 ends of the shaft, longitudinally channelled and slotted arms extending from the sleeves, a yoke slidably mounted within the channels, means within the slots for securing the yoke in adjusted position, and a shaft carried by 70 the yoke.

In testimony that I claim the foregoing as my own I have hereto affixed my signature in the presence of two witnesses.

JOHN HICKMAN ENGLEMAN.
